United States Patent Office

Des. 189,669
Patented Jan. 31, 1961

189,669

FIREARM

Wayne E. Leek, 27 Concord St., Ilion, N.Y.; Charles H. Morse, 517 Prescott St., Herkimer, N.Y.; Robert P. Kelly, 10 Spruce St., Ilion, N.Y.; James S. Martin, 4 Columbia Circle, Mohawk, N.Y.; and Paul Nasypyany, 203 E. Zoller, Herkimer, N.Y.

Filed Feb. 5, 1960, Ser. No. 59,287

Term of patent 14 years

(Cl. D30—1)

FIG.3.

FIG.4.

FIG.5.

Figure 1 is a top plan view of a firearm showing our new design;

Figure 2 is an elevational view of one side of the firearm;

Figure 3 is an elevational view of the other side of the firearm;

Figure 4 is an end elevational view from the front or muzzle end of the firearm; and

Figure 5 is an end elevational view from the back or butt end of the firearm.

We claim:

The ornamental design for a firearm, as shown.
